UNITED STATES PATENT OFFICE

WILLIS O. PROUTY, OF HERMOSA BEACH, CALIFORNIA, ASSIGNOR, BY MESNE ASSIGNMENTS, TO PROUTYLINE PRODUCTS CO., OF MANHATTAN BEACH, CALIFORNIA, A CORPORATION OF CALIFORNIA

DESIGN FOR A HAND APPLICATOR FOR LIGHT SOURCE

Application filed March 23, 1932. Serial No. 43,269. Term of patent 14 years.

To all whom it may concern:

Be it known that I, WILLIS O. PROUTY, a citizen of the United States, and a resident of the city of Hermosa Beach, county of Los Angeles, and State of California, have invented a new, original, and ornamental Design for a Hand Applicator for Light Source, of which the following is a specification, reference being had to the accompanying drawing forming part thereof, in which:

Figure 1 is a front elevation of a device embodying my invention; and

Fig. 2 is a side elevation thereof.

The essential feature of the design resides in the configuration of the casing and its handle.

I claim:

The ornamental design for a hand applicator for light source substantially as shown and described.

WILLIS O. PROUTY.
